MOVABLE TRUCK JACK

George C. Noros, Manheim, Pa., assignor to Bond
Foundry & Machine Company, Manheim, Pa.,
a corporation of Pennsylvania

Application May 11, 1940, Serial No. 334,495

16 Claims. (Cl. 280—46)

The invention relates to jacks of the character disclosed in my co-pending application for United States Letters Patent, Serial Number 299,258, filed October 13, 1939, entitled Movable truck jack, this application being in part a continuation thereof, and is especially concerned with improvements upon the jack described and claimed therein with a view to providing jacks of the same general type but somewhat better adapted for use under certain more or less unusual conditions.

More specifically while my said prior jack is entirely satisfactory when employed in mills, factories or the like where hard and reasonably uniform floors with few marked surface irregularities are normally encountered, when used in establishments such for example as potteries which sometimes have rough and uneven floors it has been found that the jack may occasionally be accidentally tilted by the floor irregularities, particularly when the truck is being pushed backwards, so as to allow the truck to fall from its elevated position and descend with considerable force upon its front supporting feet whereby if the truck is loaded with pottery or other fragile articles they may be damaged by the resultant shock.

On the other hand, in tin plate mills or the like where the jack is used for shifting trucks loaded to a considerable height above their platforms with packs of sheets or similar burdens which may also overhang the front end of the truck to some extent, it is often difficult to readily and safely disconnect the jack from the loaded truck preparatory to further use with another because the load prevents the handle from being raised sufficiently for the purpose or may be struck by the operator's hands when raising the handle while the jack is being disengaged.

The jacks of the present invention have therefore been developed more particularly with a view to meeting conditions such as those to which I have briefly referred more efficiently and safely than the jack of my prior invention and will therefore frequently be preferred for use thereunder.

It is thus a principal object of the present invention to provide a jack of the character aforesaid which in one of its embodiments has incorporated therein automatic locking means whereby accidental disconnection of the jack body from the truck coupling to which it is attached is prevented without impairment, however, of the freedom of its normal swivelling movement or its capacity for ready disconnection from the truck

when desired, and in which means are provided whereby the drawing tongue by which the jack is guided and controlled may be easily and safely manipulated when connecting the jack with a truck or disconnecting it therefrom even though the truck be loaded with more or less bulky articles to a considerable height above and sometimes in advance of its front edge.

Other objects, purposes and advantages of the invention will hereinafter more fully appear or will be understood from the following description and accompanying drawings in which

Fig. 1 is a fragmentary side elevation of the front end of a truck with one embodiment of the invention in operative association therewith.

Fig. 2 is a top plan view on a larger scale of the jack and coupling member of Fig. 1 apart from the truck;

Fig. 3 is a similarly enlarged side elevation thereof in part in vertical section on the line 3—3 in Fig. 2; and

Figs. 4, 5 and 6 are corresponding views showing another embodiment of the invention.

In the several figures like characters are used to designate the same parts, the sectional plane of Fig. 6 being indicated by the line 6—6 in Fig. 5.

Referring now more particularly to the drawings, the truck T, which may be of any suitable character, is provided with a pair of wheels at one end (not shown) while adjacent the opposite corners of its other or front end are positioned fixed supporting means such as feet F secured to a cleat C on the under side of the truck platform so the latter is maintained at its front end at substantially the same height above the floor as at its rear end when the feet are resting on the floor. Trucks of this general character are in common use and so require no further description.

In accordance with the invention a coupling 1, forming one of the two primary component elements of the jack as a whole, is permanently secured to the front end of the truck, preferably on its longitudinal center line, by screws or bolts

2 extending through ears 3 in the coupling base plate 4. The coupling has an upstanding flange

5 adapted to seat against the front edge of the truck platform and a downwardly opening, cylindrical socket 6 surrounded by a substantially circular integral flange 7, the circular bottom face of this flange forming a bearing surface on which the coupling, and hence the front end of the truck, may be supported from the other component element of the jack. The coupling is preferably made in one piece as by forging or casting

and when attached to the truck normally becomes in effect a part of it to which the said other element, now to be more fully described, may be connected or disconnected as desired.

More specifically this element, which may be termed the jack proper, comprises a generally inverted U-shaped body 10 having a center portion or bridge 11 connecting laterally spaced depending arms 12 and 13 preferably integral therewith. The upper surface of the bridge is plane and from it rises a cylindrical pintle 15 desirably somewhat tapered at its end to facilitate its insertion into the coupling socket 6, said plane surface on the bridge forming a platform upon which the bottom face of the coupling rests when the pintle is seated in the socket. Extending upwardly from the front edge of the bridge 11 is an overhanging generally segmental lip 16 which cooperates with the bridge to form a groove or track 17 for the front edge of the flange 7 when the pintle is in the socket and allows for movement of the jack relatively to the coupling about the axis of the pintle.

To prevent accidental disengagement of the jack from the coupling when the truck is being backed over a rough floor or encounters an obstruction, in that form of the invention shown in Figs. 1-3 a latch 19 is pivoted on a pin 20 extending between the arms 12 and 13 of the body 10 and adapted to overlie the rear edge of the flange 7 when the jack is in operative association with the coupling. The latch is normally held in this position as shown in full lines in Figs. 1 and 3 by springs 21 recessed in the forwardly projecting actuating lever 22 of the latch and in the bridge 11 respectively, the lever 22 having an aperture 23 through which extends an abutment 24 depending from the bridge 11 for a purpose which will hereinafter appear. The upper end of the latch is curved as at 19a and the lower corner of flange 7 rounded off to enable the latch to readily ride over it when the jack is being connected to the coupling.

Bosses 25 are formed at the lower extremities of the depending arms 12, 13 and are bored to receive a transverse axle 26 on the ends of which wheels 27 are rotatably mounted and held in place by cotter pins 28 and washers 29 or in any other convenient way.

The arms 12 and 13 are also extended rearwardly as at 30 and bored to receive a pivot pin 31 parallel to the axle 26 which is held in the arms by cotter pins 32 and a guiding tongue 33 is attached to the jack by means of this pin. The tongue is desirably tubular, of rectangular cross-section, curving downwardly and rearwardly from its upper forward end, provided with a transverse handle 34, to its rear lower end which extends between the arms 12 and 13 and receives the square shank 35 of a head 36 secured in the tongue by a pin 37 and having an oppositely tapered transverse hole 38 which loosely receives the pivot pin 31, as best shown in Fig. 3, to permit pivotal movement of the head and hence of the tongue about the pin.

Adjacent their front edges the arms 12 and 13 are provided with inwardly projecting abutments 39 spaced apart sufficiently to permit the tongue 33 to move vertically between them about its pivot pin 31 whereby the height of the handle 34 above the floor can be varied to enable the operator to conveniently move and guide the truck, the tongue engaging one or the other of the abutments when the jack is to be turned about

the pintle 15 as the truck is being pulled or pushed around.

The tongue is also provided at a point near the front of the jack body with a latch operating dog 40 comprising vertical flanges 41 lying on opposite sides of the tongue and pivoted thereto on a transverse pivot 42, and oppositely laterally and forwardly extending pedal parts 43 which enable the operator to move the dog 40 about its pivot with his foot to swing it from one to another of the positions respectively indicated in full and in broken lines in Fig. 3. The dog 40 is formed near one end for engagement in a notch 44 in the front end of the lever 22 when the dog is moved about its pivot from full to broken line position in Fig. 3 to thereby raise the lever against the force of its springs 21 and clear it from the flange 7 on the coupling, and after the latch has thus been cleared from the flange the operator by lifting the tongue can swing the entire jack proper forwardly about the front edge of the flange to withdraw the pintle 15 from the socket 6, thus lowering the front end of the truck onto its feet F. The interposition of the dog 40 between the lowered tongue and the raised latch lever prevents relative movement between the jack body and the tongue during this operation and complete control of the jack and truck while the latter is being lowered is thereby afforded. However, the tongue can be freely moved vertically about its pivot pin 31 to a height which suits the operator's convenience without disturbing the normal locking relation of the latch with the flange when the dog 40 is retracted to full line position and the abutment 24 then serves as a stop to prevent the tongue being raised high enough to operate the latch and permit inadvertent disconnection of the jack from the truck.

The jack may be connected with the coupling to raise the truck end from the floor irrespective of the position of the dog 40 although the latter will ordinarily be in its dotted line or operative position during this operation, having been brought thereto when uncoupling the jack from the preceding truck and subsequently left therein. Therefore, assuming the dog is in that position and the tongue consequently substantially in engagement with the axle 26, the jack is moved toward the coupling so as to bring the tapered end of pintle 15 into the socket 6, the flange 7 on the coupling entering groove 17 formed by lip 16 on the jack bridge during this movement; downward and rearward pressure on the tongue in engagement with the axle then slides the bridge of the jack under flange 7 to lift the truck end and finally bring the cooperative plane faces of the bridge and coupling together as the pintle slides into the coupling socket where it serves as a king bolt on which the jack can now turn for steering the truck. The jack is preferably so constructed that when the operation just described is completed, axle 26 is just "over center" with respect to the axis of pintle 15 and the dog 40 may now be retracted to permit the latch 19 to move to latching position in which it overhangs the flange 7 and its arm 22 rests on the abutments 39 which are so positioned that the latch is normally held just out of engagement with the flange. If, however, the dog is in inoperative position and the latch consequently in latching position when the jack is being connected to the coupling, the rounded end 19a of the latch rides over the lower face and corner of the flange 7 as the jack is moved in.

under it and as the pintle 15 fully enters its socket the latch, under the bias of its spring, snaps into latching position and the arm 22 comes to rest on the abutments.

The latch is thus normally held just out of engagement with the flange but in position to engage it whenever the jack is moved relatively to the coupling in a manner tending to swing it forwardly about the front lower edge of the flange; consequently the jack cannot be separated from the truck unless the latch is positively operated by the dog 40, and if the dog is kept retracted (as in Fig. 1) when the truck is being moved about it cannot be accidentally engaged with the latch to release the latter.

Under normal conditions of use the jack is therefore at all times maintained in non-separable relation to the coupling and the truck may be moved over rough or uneven surfaces without danger, although the jack may be readily disconnected from the truck when desired; the dog 40, moreover, enables the disconnection to be effected without swinging the handle upwardly to an inconvenient height or too closely to material on the truck even when piled to a considerable height and/or partially overhanging its front end.

The jack shown in Figs. 4, 5 and 6 is simpler in its construction than that shown in the preceding figures in that it does not include a latch for releasably maintaining its attachment to the coupling 1'; the parts of the latter, however, as well as some parts of the jack proper may be generally similar to corresponding parts shown and described in my said prior application Serial No. 299,258. Thus the flange 1' on the coupling 1' may be segmental instead of circular and is adapted for reception in the groove 17' formed by lip 16' with the bridge 11' of the jack body when the pintle 15' on the latter is entered in the coupling socket 6', while the tongue 33', pivoted on a pin 31' between the arms 12', 13' of the jack body, may be raised and moved laterally into either of the spaces or notches between the upper ends of abutments 39' and the bevelled surface 24' on the lower face of the bridge 11' when the jack is being connected to or disconnected from the coupling, substantially in the same manner as in the operation of the jack disclosed in said application. However, as noted, this is sometimes difficult of accomplishment and may involve risk of injury to the operator under certain load conditions of the truck, so in accordance with the present invention I therefore arrange upon the tongue a dog 40' of such character and in such a way that it may be interposed between the latter and the surface 24' on the bridge when the tongue is depressed substantially in engagement with the axle 26' to thereby enable the jack to be manipulated without requiring the handle 34' to be raised sufficiently to strike or come into close proximity to the load upon the truck. The dog is pivotally supported on the tongue through the medium of vertical flanges 41', preferably integral with the dog, which are pivoted on opposite sides of the tongue on a transverse pivot 42' while forwardly and laterally extending pedal parts 43' formed on the flanges enable the operator to easily and conveniently swing the dog 40' about its pivot with his foot and thus move it from the full line or operative position of Fig. 6 to the dotted or inoperative one or vice versa, the dog when in the former position facilitating connection of

the jack to, or its disconnection from the truck without the necessity of materially raising the tongue relatively to the jack body and when in the latter position enabling the tongue to be moved freely about its pivot 31' for adjustment of the handle 34' to a convenient height for guiding and controlling the jack in moving the truck.

This jack is thus designed primarily for, and is well adapted to, use in sheet and plate mills and the like in which trucks are generally piled high with non-yielding and often overhanging articles but are not likely to be pushed over rough or uneven floors and therefore do not need to have the jack positively locked to the coupling.

As will now be apparent, jacks constructed in accordance with the present invention are particularly adapted for certain special purposes and are not primarily intended for the more general uses for which the jack described and claimed in my said prior application is eminently suited.

Consequently, while I have herein shown and described with considerable detail certain embodiments of the present invention, and have pointed out particularly wherein I consider it an improvement over my said prior invention, it is to be distinctly understood I do not thereby intend or wish to be limited or confined thereto in any way, as changes and modifications in the form, structure and arrangement of the several parts and their mode of cooperation will readily occur to those skilled in the art and may be made if desired without departing from the spirit and scope of the invention as defined in the appended claims.

Having thus described my invention, I claim and desire to protect by Letters Patent of the United States:

1. A truck jack of the character described comprising a pair of coaxial wheels, a body supported therefrom including a pair of upstanding arms and means interconnecting the arms above the axis of the wheels, a tongue pivoted to the arms and extending therebetween and means carried by the tongue adapted for interposition between the tongue and said arm connecting means effective when so interpositioned to limit pivotal movement of the tongue relatively to the body.

2. A truck jack of the character described, comprising a pair of wheels, an axle carried thereby, a body supported from the axle including spaced upstanding arms and a bridge paralleling the axle adjacent the extremities of the arms, a tongue pivoted between the arms selectively movable into engagement with the axle and the bridge and means pivoted to the tongue adapted for interposition between the tongue and the bridge when the tongue is in engagement with the axle to thereby limit pivotal movement of the tongue toward the bridge.

3. A truck jack of the character described, comprising a pair of coaxial wheels, a pair of upstanding arms supported therefrom, a bridge connecting the arms, a tongue pivoted to the arms on one side of the wheel axis and extending therebetween to the opposite side of said axis and movable on its pivot into engagement with the bridge, and means carried by the tongue and pivoted thereto adapted for interposition between the tongue and the bridge to thereby limit pivotal movement of the tongue toward the bridge.

4. A truck jack of the character described, comprising a pair of wheels, an axle carried there-

by, a jack body supported from the axle and comprising spaced upstanding arms and a bridge paralleling the axle adjacent the extremities of the arms, a tongue pivoted between the arms selectively movable into engagement with the axle and the bridge and means pivoted to the tongue adapted for interposition between the tongue and the bridge to limit said pivotal movement and maintain the tongue in substantial engagement with said axle.

5. In combination with a truck of the character described, a coupling secured to the truck and a jack cooperative with the coupling comprising means forming a pivotal connection with the coupling, coaxial wheels, a body interconnecting said means and said wheels, a lip on the body coaxial with said pivotal connection adapted to overhang a portion of the coupling, a tongue pivoted to the body and extending between the arms and means pivoted to the tongue adapted when in one position to limit movement thereof relatively to the body and thereby enable the body to be turned about the axis of the wheels by movement of the tongue.

6. A truck jack of the character described, comprising a body having a bridge and laterally spaced arms depending therefrom, coaxial supporting wheels rotatively supported from the arms, a tongue extending between the arms and across said axis, pivoted to the arms on one side of said axis and movable on its pivot in a plane substantially normal thereto, and means pivoted to the body for movement in substantially the same plane adapted to releasably secure the jack to a truck.

7. A truck jack of the character described, comprising a body having a bridge and laterally spaced arms depending therefrom, coaxial supporting wheels rotatively supported from the arms, a tongue extending between the arms pivoted thereto on one side of the wheel axis and extending beyond the other side of said axis, the tongue being movable on its pivot in a plane substantially normal to said axis, a movable coupling-engaging latch carried by the body and extending between the bridge and the tongue and means pivoted to the latter for movement in said plane operable to move the latch from coupling-engaging position.

8. A truck jack of the character described, comprising a body having a bridge and laterally spaced arms depending therefrom, coaxial supporting wheels rotatively supported from the arms, a tongue pivoted to and extending between the arms, a segmental lip projecting upwardly from the bridge, a coupling member on the bridge coaxial with the lip adapted for cooperation with a complementary coupling element on a truck, latching means pivoted to the body and projecting upwardly beyond the bridge in substantially diametric opposition to said lip for releasably securing the jack to said element and means carried by the tongue for actuating said latching means.

9. In combination with a truck of the character described, a coupling secured to the truck and a jack comprising a body, cooperative means respectively carried by the coupling and body forming a pivotal connection therebetween, coaxial wheels rotatively attached to the body, an upwardly directed lip on the body adapted to overhang a portion of the coupling and means cooperative with the lip to releasably maintain said pivotal connection between the body and coupling.

10. In combination with a truck of the character described, a coupling secured to the truck and a jack cooperative with the coupling comprising means forming a pivotal connection with the coupling, coaxial wheels, a body interconnecting said means and said wheels, a lip on the body coaxial with said pivotal connection adapted to overhang a portion of the coupling and means pivoted to the body and projecting therefrom in substantially diametric opposition to said lip with respect to the axis of said connection cooperative with the lip to releasably maintain the jack in pivotal relation with the coupling.

11. In combination with a truck of the character described, a coupling secured to the truck and a jack cooperative with the coupling comprising a body, means carried by the body forming a pivotal connection with the coupling, coaxial wheels rotatively attached to the body, means pivoted to the body adapted to engage the coupling to maintain said pivotal connection, a tongue pivoted to the body for guiding and controlling the jack and means carried by the tongue operable to actuate said last mentioned means to enable the body to be separated from the coupling.

12. In combination with a truck of the character described, a coupling secured to the truck and a jack comprising a body, cooperative means respectively carried by the coupling and body forming a pivotal connection therebetween, coaxial wheels rotatively attached to the body, an upwardly directed lip on the body adapted to overhang a portion of the coupling, means cooperative with the lip to releasably maintain said pivotal connection between the body and coupling, a tongue carried by the body for guiding the jack and means carried by the tongue operable to actuate said releasable means when it is desired to disconnect the jack from the coupling.

13. In combination with a truck of the character described, a coupling secured to the truck and a jack pivotally connected with the coupling comprising coaxial wheels, a body carried by said wheels and adapted to support the coupling, a latch pivoted to the body and engageable with the coupling to releasably maintain the jack in pivotal relation therewith, the latch comprising an apertured arm extending within the body for movement in a plane normal to the wheel axis, a tongue pivoted to the body for movement in a like plane, means carried by the tongue adapted for interposition between the tongue and arm to actuate the latch and means projecting from the body toward the tongue and extending through the aperture in the arm adapted to limit movement of the tongue in one direction in said plane and prevent the jack from becoming disengaged.

14. In a jack of the character described adapted for cooperative attachment to a coupling, means adapted to form a pivotal connection with the coupling, coaxial wheels, a body interconnecting said means and said wheels, a movable latch carried by the body adapted to releasably lock it to the coupling in pivotal relation therewith, the latch having an operating arm movable in a plane normal to the wheel axis, a tongue pivoted to the body for movement in a like plane, means pivoted to the tongue operable to actuate the arm to move the latch and means projecting from the body into the path of the tongue adapted to limit movement of the tongue in one direction and prevent the jack from becoming disengaged.

15. In combination with a truck of the character described, a coupling secured to the truck and a jack cooperative with the coupling comprising means forming a pivotal connection with the coupling, coaxial wheels, a body interconnecting said means and said wheels, a lip on the body coaxial with said pivotal connection adapted to overhang a portion of the coupling and means pivoted to the body and projecting therefrom in substantially diametric opposition to said lip with respect to the axis of said connection cooperative with the lip to releasably maintain the jack in pivotal relation with the coupling, said means including an arm extending substantially normal to said axis and yielding means engaging the arm 15 normally operative to hold said means in position for maintaining said pivotal connection.

16. In combination with a truck of the character described, a coupling secured to the truck and a jack cooperative with the coupling comprising means forming a pivotal connection with the coupling, coaxial wheels, a body interconnecting said means and said wheels, a lip on the body coaxial with said pivotal connection adapted to overhang a portion of the coupling, a spring pressed pivoted latch projecting upwardly from the body cooperative with the lip to releasably lock the body to the coupling, a tongue pivoted to the body for guiding and controlling the jack and means pivoted to the tongue operable to actuate the latch.

GEORGE C. NOROS.
